UNITED STATES PATENT OFFICE.

JOHN A. MILLER, OF HOMEWOOD, ILLINOIS.

PLEASURE-RAILWAY STRUCTURE.

Application filed May 23, 1925. Serial No. 32,256.

To all whom it may concern:

Be it known that I, JOHN A. MILLER, a citizen of the United States, residing at Homewood, in the county of Cook and State 5 of Illinois, have invented certain new and useful Improvements in Pleasure-Railway Structures, of which the following is a full, clear, concise, and exact description, reference being had to the accompanying drawings, forming a part of this invention.

My invention relates to pleasure railway structures and particularly to improved track construction therefor.

The invention covers an improved track 15 structure in which stringer structures built up of lengths of timber, provide a yielding seat for the actual rails formed of steel parts which provide steel trackage surface for the 20 wheels of the cars and also for the safety rollers and abutments for keeping the cars to the rails, the wooden stringer structure accurately following the curvature of the 25 rails and cushioning the travel over the rails and deadening noise.

The important object is to build up the 30 steel rail structure of steel stock bars which can be easily bent with comparatively light machinery to fit the curves, both lateral and vertical, on a pleasure railway structure. The 35 particular arrangement to be covered in this application is clearly disclosed on the drawing, on which

Fig. 1 is a side-elevational view of the end 40 of a car and the improved track structure therefor;

Fig. 2 is a sectional view on plane 2-2 of Fig. 1; and

Fig. 3 is a plan view of the rail structure 45 on line 3-3 of Fig. 2.

Referring to Fig. 1, ties 10 are supported on the structural work 11 which rests on the ground. The stringer structure shown comprises the flat timbers or planks 12, whose ends overlap, as shown in Fig. 1. On top 50 of these planks are the timbers 13 set on edge and side by side. Bolts 14 extend through these timbers, the planks 12 and the ties 10, so that the elements of the stringer structure are rigidly secured together and to the ties. This laminated stringer structure is very 55 resilient, but of considerable strength. Supported on the stringer structure are the rail structures shown as comprising L bars 15 and flat top bars 16. The timbers 13 are set 60 a distance away from the inner sides of the planks 12 to leave a rectangular recess 17

for receiving the angle bar elements of the rail structure, the vertical webs of these angle bars being of the same height as the timbers 13. The top flat bars 16 of the rail structure rest on top of the angle bars and at their inner sides overhanging and resting on top of the beam 13. As shown, the bars engage along their longitudinal center line 65 on top of the vertical web of the angle bars. The timbers 13 are secured together by bolts 18 and these also extend through the vertical web of the angle bars, to thus secure the angle bars in place, while the inner bolts 14 extend through the rail bars 16 and secure 70 them in place. The bolts holding the rail parts are countersunk so that these rail parts will present smooth rail surfaces.

The car C shown has the cylindrical vehicle wheels 20, and these wheels have traction on the rail bars 16. Adjacent to each vehicle wheel, the car body supports the horizontal safety roller or wheel 21. The cylindrical surface of this safety roller engages with the inner face of the web of the 75 rail angle bars 15 to limit the lateral play of the cars, while the upper rounded corner 22 of the wheel cooperates with the under side of the rail bars 16 to limit the vertical 80 displacement of the car as it travels along the track structure and around lateral and vertical curves. The vehicle wheels are so positioned that they will tend to keep on the centers of the rails, that is, vertically over the vertical web thereof, and the horizontal 85 web of the angle bar members will form a supporting base and will assist the rail bars in supporting the vertical load. There is sufficient clearance between the safety wheels and the rails to allow a certain degree of 90 lateral and vertical play for the cars as they travel over the track.

The angle bar lengths and the flat bar 95 lengths can be readily and accurately bent to fit the various curves, declines, summits, etc., of the track structure and after bending they can be readily applied to the wooden 100 laminated stringer structure, which stringer structure will give a resilient and cushioning support to the rails and insure 105 easy and comfortable riding of the cars and will absorb the noise. The rail sections can also be welded together end to end, which will increase the strength of the track structure and will also present a smooth and 110 continuous rail surface for the vehicle and safety wheels. The wooden beams and

planks making up the stringer structure, and also the angle bars and flat bars forming the rail structure, can be of standard stock size so that no special work is necessary and the cost of the structure is materially reduced. The wooden beams are assembled and secured together to follow the prescribed curvature for the track structure and then the rail members are seated 5 in the recesses 17 and secured in place, the wooden stringer structure forming the resilient seating and backing support for the rail structure.

I claim:—

- 15 1. In a pleasure railway track construction, the combination of stringers, and rail structures on said stringers comprising angle bars and flat bars, said angle bars engaging with their backs and bottoms 20 against said stringers, and said flat bars seating on top of said stringers and angle bars and overhanging the angle bar bases.
2. In a pleasure railway track construction, the combination of a supporting 25 stringer having a step along its inner side, and a rail structure comprising an angle bar and a flat bar, said angle bar resting on said step and said flat bar being supported on top of the stringer and said angle bar 30 and overhanging the angle bar base, said flat bar forming a rail surface for vehicle wheels and said flat bar and angle bar forming a groove for cooperating with safety abutments.
- 35 3. In pleasure railway track construction, the combination of a stringer structure comprising upper and lower sections, said upper section being off-set outwardly on the lower section to leave a recess along 40 the inner side of the structure, angle bars secured in said recess, and rail bars secured on top of the upper part of said stringer structure and resting on top of said angle bars and overhanging the angle bar bases.
- 45 4. In pleasure railway track construction,

the combination of a stringer structure having a ledge along its inner side, angle bars seating on said ledge and against the stringer structure, and flat rail bars supported on said stringer structure and 50 engaging along their longitudinal median lines on said angle bars to overhang the angle bar bases.

5. In pleasure railway track construction, the combination of a supporting 55 stringer having a step on its inner side, and a rail structure comprising a vertical web part engaging against the vertical face of said step, and a base part seating on the horizontal part of said step, and a flat top 60 part resting on top of said stringer and overhanging said base part.

6. In pleasure railway track construction, the combination of a stringer structure comprising a lower part and an upper 65 part set inwardly from the inner edge of the lower part to form a recess, vertical bolts securing said parts together, and a rail structure comprising commercial angle bars seating in said recess and secured to 70 the stringer structure, and flat top bars secured by some of said bolts to said stringer structure and overhanging the base of the angle bars.

7. In pleasure railway track construction, the combination of a resilient stringer structure and a rail structure comprising commercial angle bars and flat bars, said angle bars being seated and backed up by 75 said stringer structure, and said flat bars being secured on top of the stringer structure and resting on the upper edges of said angle bars and overhanging the angle bar bases, said bars forming a rail surface for vehicle wheels and said flat bars and angle 80 bars forming a safety abutment receiving groove.

In witness whereof, I hereunto subscribe my name this 15th day of May, 1925.

JOHN A. MILLER.
